UNITED STATES PATENT OFFICE

125,623

DESIGN FOR A PLATE OR SIMILAR ARTICLE

Alexander W. Mackenzie, Jr., Upper Montclair,
N. J., assignor to Meakin & Ridgeway, Inc., New York, N. Y., a corporation of New York

Application December 21, 1940, Serial No. 97,519

Term of patent 7 years

To all whom it may concern:

Be it known that I, Alexander W. Mackenzie, Jr., a citizen of the United States of America, and a resident of Upper Montclair, in the county of Essex, State of New Jersey, have invented a new, original, and ornamental Design for a Plate or Similar Article, of which the following is a specification, reference being had to the accompanying drawing, forming part thereof.

The drawing represents a plan view of a plate showing my new design, it being understood that the border decoration as shown in the drawing is continued around the border of the article.

I claim:

The ornamental design for a plate or similar article, as shown and described.

ALEXANDER W. MACKENZIE, JR.
